CLAIM

The ornamental design for a photograph storage and display case, substantially as shown and described.

DESCRIPTION

FIG. 1 is a perspective view of a photograph storage and display case showing my new design;

FIG. 2 is a top plan view thereof;

FIG. 3 is a front elevational view thereof;

FIG. 4 is a left side elevational view thereof, the right side being identical with the left side; and

FIG. 5 is a rear elevational view thereof.
